Primary Examiner — Caron D Veynar*Assistant Examiner* — Mehri F Bajoul(74) *Attorney, Agent, or Firm* — Grogan, Tuccillo & Vanderleeden, LLP(57) **CLAIM**

The ornamental design for a stand mixer, as shown and described.

DESCRIPTION

FIG. 1 is a left side elevational view of a stand mixer showing a new design;

FIG. 2 is a front elevational view thereof;

FIG. 3 is a right side elevational view thereof;

FIG. 4 is a rear elevational view thereof;

FIG. 5 is a top plan view thereof;

FIG. 6 is a bottom plan view thereof;

FIG. 7 is a left front side, perspective view thereof;

FIG. 8 is a right rear side, perspective view thereof;

FIG. 9 is a left rear side, perspective view thereof; and,

FIG. 10 is a right front side, perspective view thereof.

In the drawings the broken lines are included to depict portions of the stand mixer that form no part of the claimed design.

The broken lines are for illustrative purposes only and form no part of the claimed design.

“Cuisinart” is a trademark owned by Conair Corporation, having business address at One Cummings Point Road Stamford, Conn. 06902. The trademark Cuisinart, as amended, is in broken lines and forms no part of the claimed design.

1 Claim, 10 Drawing Sheets(56)
